(57) **ABSTRACT**

A method for manufacturing a nozzle cap, the method including attaching an antenna printed circuit board (“PCB”) strip to an inner cover surface of an antenna cover; and inserting the antenna cover into a scallop defined by a circumferential wall of a cap body to position the antenna PCB strip between the antenna cover and the circumferential wall, the circumferential wall defining an outer wall surface, the antenna cover covering the scallop, the scallop extending radially inward into the circumferential wall relative to a first portion and a second portion of the outer wall surface, the scallop circumferentially positioned between the first portion and the second portion of the outer wall surface.

NOZZLE CAP ENCAPSULATED ANTENNA SYSTEM

CROSS-REFERENCE TO RELATED APPLICATIONS

This application is a continuation of U.S. patent application Ser. No. 16/234,715, filed Dec. 28, 2018, which is hereby incorporated by reference in its entirety.

TECHNICAL FIELD

This disclosure relates to nozzle caps. More specifically, this disclosure relates to a nozzle cap of a fire hydrant which is configured to wirelessly transmit a signal.

BACKGROUND

Some fluid systems, such as water distribution systems, can comprise fire hydrants which can be attached to legs of the fluid system, such as a water main. Fire hydrants typically have one or more nozzles sealed with a nozzle cap. In an Advanced Metering Infrastructure, the fire hydrants can be configured to wirelessly transmit data. For example, the nozzle cap of a fire hydrant can contain a vibration sensor configured to detect leaks within the fluid system, and information about the presence or absence of leaks can be wirelessly transmitted to an agency tasked with managing and maintaining the water distribution system. However, nozzle caps configured to wirelessly transmit information can contain delicate electronics which can easily be damaged by impacts, as nozzle caps commonly experience. Additionally, the fire hydrants and nozzle caps are commonly made of metal which can interfere with wireless transmission of a signal from within a nozzle cap.

SUMMARY

It is to be understood that this summary is not an extensive overview of the disclosure. This summary is exemplary and not restrictive, and it is intended to neither identify key or critical elements of the disclosure nor delineate the scope thereof. The sole purpose of this summary is to explain and exemplify certain concepts of the disclosure as an introduction to the following complete and extensive detailed description.

Disclosed is a method for manufacturing a nozzle cap, the method comprising: attaching an antenna printed circuit board (“PCB”) strip to an inner cover surface of an antenna cover; and inserting the antenna cover into a scallop defined by a circumferential wall of a cap body to position the antenna PCB strip between the antenna cover and the circumferential wall, the circumferential wall defining an outer wall surface, the antenna cover covering the scallop, the scallop extending radially inward into the circumferential wall relative to a first portion and a second portion of the outer wall surface, the scallop circumferentially positioned between the first portion and the second portion of the outer wall surface.

Also disclosed is a nozzle cap comprising: a cap body defining a circumferential wall, the circumferential wall defining an outer wall surface, a scallop defined extending into the circumferential wall relative to a first portion and a second portion of the outer wall surface, the scallop circumferentially positioned between the first portion and the second portion of the outer wall surface; an antenna cover positioned within the scallop, the antenna cover secured to

the cap body by at least one pin; and an antenna printed circuit board (“PCB”) strip positioned within an antenna cavity defined between the antenna cover and the circumferential wall.

Also disclosed is a method for manufacturing a nozzle cap, the method comprising: positioning a first antenna cover in a first scallop of a circumferential wall of a cap body with a first antenna printed circuit board (“PCB”) strip positioned between the first antenna cover and the circumferential wall, the circumferential wall defining an outer wall surface, the first scallop extending inwards relative to a first portion and a second portion of the outer wall surface, the first scallop circumferentially positioned between the first portion and the second portion of the outer wall surface; and positioning a second antenna cover in a second scallop of the circumferential wall with a second antenna PCB strip positioned between the second antenna cover and the circumferential wall.

Various implementations described in the present disclosure may include additional systems, methods, features, and advantages, which may not necessarily be expressly disclosed herein but will be apparent to one of ordinary skill in the art upon examination of the following detailed description and accompanying drawings. It is intended that all such systems, methods, features, and advantages be included within the present disclosure and protected by the accompanying claims. The features and advantages of such implementations may be realized and obtained by means of the systems, methods, features particularly pointed out in the appended claims. These and other features will become more fully apparent from the following description and appended claims, or may be learned by the practice of such exemplary implementations as set forth hereinafter.

BRIEF DESCRIPTION OF THE DRAWINGS

The features and components of the following figures are illustrated to emphasize the general principles of the present disclosure. The drawings are not necessarily drawn to scale. Corresponding features and components throughout the figures may be designated by matching reference characters for the sake of consistency and clarity.

FIG. 1 is a perspective view of a fire hydrant comprising a barrel, a nozzle cap, and a bonnet in accordance with one aspect of the present disclosure.

FIG. 2 is a front perspective view of the nozzle cap of FIG. 1 comprising a cap body and a cap cover attached to the cap body by fasteners.

FIG. 3 is a front view of the nozzle cap of FIG. 1 facing a first body end of the cap body with the cap cover and the fasteners removed.

FIG. 4 is a front perspective view of the nozzle cap of FIG. 1, with a cavity gasket of the nozzle cap additionally removed.

FIG. 5 is a front perspective view of the nozzle cap of FIG. 1, with the antenna covers and the antenna printed circuit board (“PCB”) strips of the nozzle cap additionally removed.

FIG. 6 is a front perspective view of the nozzle cap of FIG. 1, with the spacer strips, the plugs, and the pins of the nozzle cap additionally removed.

FIG. 7 is a side view of the nozzle cap of FIG. 1, as configured in FIG. 6.

FIG. 8 is a front exploded view of the cap body, the plugs, the pins, the spacer strips, the antenna PCB strips, and the antenna covers of the nozzle cap of FIG. 1.

FIG. 9 is a front view of an antenna PCB strip comprising a Global System for Mobile communications (“GSM”) antenna according to another aspect of the present disclosure.

FIG. 10 is a front view of an antenna PCB strip comprising an Advanced Meter Infrastructure (“AMI”) antenna according to another aspect of the present disclosure.

FIG. 11 is a front view of an antenna PCB strip comprising a Global Positioning System (“GPS”) antenna according to another aspect of the present disclosure.

FIG. 12 is a front view of an antenna PCB strip comprising a Near Field Communication (“NFC”) antenna according to another aspect of the present disclosure.

DETAILED DESCRIPTION

The present disclosure can be understood more readily by reference to the following detailed description, examples, drawings, and claims, and the previous and following description. However, before the present devices, systems, and/or methods are disclosed and described, it is to be understood that this disclosure is not limited to the specific devices, systems, and/or methods disclosed unless otherwise specified, and, as such, can, of course, vary. It is also to be understood that the terminology used herein is for the purpose of describing particular aspects only and is not intended to be limiting.

The following description is provided as an enabling teaching of the present devices, systems, and/or methods in its best, currently known aspect. To this end, those skilled in the relevant art will recognize and appreciate that many changes can be made to the various aspects of the present devices, systems, and/or methods described herein, while still obtaining the beneficial results of the present disclosure. It will also be apparent that some of the desired benefits of the present disclosure can be obtained by selecting some of the features of the present disclosure without utilizing other features. Accordingly, those who work in the art will recognize that many modifications and adaptations to the present disclosure are possible and can even be desirable in certain circumstances and are a part of the present disclosure. Thus, the following description is provided as illustrative of the principles of the present disclosure and not in limitation thereof.

As used throughout, the singular forms “a,” “an” and “the” include plural referents unless the context clearly dictates otherwise. Thus, for example, reference to “an element” can include two or more such elements unless the context indicates otherwise.

Ranges can be expressed herein as from “about” one particular value, and/or to “about” another particular value. When such a range is expressed, another aspect includes from the one particular value and/or to the other particular value. Similarly, when values are expressed as approximations, by use of the antecedent “about,” it will be understood that the particular value forms another aspect. It will be further understood that the endpoints of each of the ranges are significant both in relation to the other endpoint, and independently of the other endpoint.

For purposes of the current disclosure, a material property or dimension measuring about X or substantially X on a particular measurement scale measures within a range between X plus an industry-standard upper tolerance for the specified measurement and X minus an industry-standard lower tolerance for the specified measurement. Because tolerances can vary between different materials, processes

and between different models, the tolerance for a particular measurement of a particular component can fall within a range of tolerances.

As used herein, the terms “optional” or “optionally” mean that the subsequently described event or circumstance can or cannot occur, and that the description includes instances where said event or circumstance occurs and instances where it does not.

The word “or” as used herein means any one member of a particular list and also includes any combination of members of that list. Further, one should note that conditional language, such as, among others, “can,” “could,” “might,” or “may,” unless specifically stated otherwise, or otherwise understood within the context as used, is generally intended to convey that certain aspects include, while other aspects do not include, certain features, elements and/or steps. Thus, such conditional language is not generally intended to imply that features, elements and/or steps are in any way required for one or more particular aspects or that one or more particular aspects necessarily include logic for deciding, with or without user input or prompting, whether these features, elements and/or steps are included or are to be performed in any particular aspect.

Disclosed are components that can be used to perform the disclosed methods and systems. These and other components are disclosed herein, and it is understood that when combinations, subsets, interactions, groups, etc. of these components are disclosed, that while specific reference of each various individual and collective combinations and permutations of these may not be explicitly disclosed, each is specifically contemplated and described herein, for all methods and systems. This applies to all aspects of this application including, but not limited to, steps in disclosed methods. Thus, if there are a variety of additional steps that can be performed it is understood that each of these additional steps can be performed with any specific aspect or combination of aspects of the disclosed methods.

Disclosed is a nozzle cap and associated methods, systems, devices, and various apparatus. The nozzle cap can comprise a cap body, a pair of antenna printed circuit boards (“PCBs”) strips, and a pair of antenna covers. It would be understood by one of skill in the art that the disclosed nozzle cap is described in but a few exemplary aspects among many. No particular terminology or description should be considered limiting on the disclosure or the scope of any claims issuing therefrom.

FIG. 1 is a perspective view of a fire hydrant 110 comprising a barrel 120, a nozzle cap 150, and a bonnet 180. The barrel 120 can define a top barrel end 122 and a bottom barrel end 124 disposed opposite from the top barrel end 122. The barrel 120 can be substantially tubular. The barrel 120 can comprise a top flange 126 disposed at the top barrel end 122 and a base flange 128 disposed at the bottom barrel end 124. The base flange 128 can be fastened to a stand pipe flange 199 of a stand pipe 198 of a fluid system (not shown), such as a water main for example and without limitation. The base flange 128 can be fastened to the stand pipe flange 199 by a plurality of fasteners 130. A bonnet flange 182 of the bonnet 180 can be attached to the top flange 126 of the barrel 120, such as with a plurality of fasteners (not shown) similar to the fasteners 130. The bonnet 180 can comprise an operation nut 184, or “op nut”, which can be rotated to open and close a main valve (not shown) positioned at the bottom barrel end 124 or below in the stand pipe 198 in order to respectively supply or cut off pressurized water supply to the fire hydrant 110.

The barrel 120 can define one or more nozzles 140a,b. The nozzle cap 150 can be screwed onto the nozzle 140a to seal the nozzle 140a. With the nozzle cap 150 sealing the nozzle 140a, pressurized water cannot escape through the nozzle 140a when the main valve (not shown) is in an open position. The nozzle cap 150 can define a cap nut 152 which can be turned, such as with a wrench, to tighten or loosen the nozzle cap 150 on the nozzle 140a.

FIG. 2 is a perspective front view of the nozzle cap 150 of the fire hydrant 110 of FIG. 1. The nozzle cap 150 can comprise a cap body 210, a cap cover 280, and a pair of antenna covers 318a,b. The cap body 210 can define a first body end 212 and a second body end 214, and the first body end 212 can be disposed opposite from the second body end 214. The cap body 210 can define a cap axis 201 extending from the first body end 212 to the second body end 214. The cap axis 201 can extend through the cap nut 152 such that rotating the nozzle cap 150 by turning the cap nut 152, such as with a wrench, can rotate the nozzle cap 150 about the cap axis 201.

The cap body 210 can define a pair of bottom shelves 240a,b at the second body end 214. Each bottom shelf 240a,b can respectively be positioned beneath a different one of the antenna covers 318a,b with respect to the present viewing angle. The cap cover 280 can be secured to the first body end 212 by a plurality of fasteners 230. The bottom shelves 240a,b and the cap cover 280 can radially overlap with each of the antenna covers 318a,b, respectively, to axially secure each antenna cover 318a,b between the respective bottom shelf 240a,b and the cap cover 280 relative to the cap axis 201.

The cap body 210 can also define a circumferential wall 312 extending from the first body end 212 towards the second body end 214, and each antenna cover 318a,b can circumferentially overlap a different portion of the circumferential wall 312. In the present aspect, each antenna cover 318a,b can respectively define an outer cover surface 218a,b, and the circumferential wall 312 can define an outer wall surface 290. In the present aspect, each of the outer cover surfaces 218a,b can be positioned flush with the outer wall surface 290.

FIG. 3 is a front view of the nozzle cap 150 of FIG. 1 facing the first body end 212 with the cap cover 280 (shown in FIG. 2) and fasteners 230 (shown in FIG. 2) removed to expose a cavity 310 within the cap body 210. The cap body 210 can define fastener holes 330 configured to receive the fasteners 230 to secure the cap cover 280 to the cap body 210. The cavity 310 can extend inwards into the cap body 210 from the first body end 212 to an inner wall 220 of the cap body 210. As shown, the circumferential wall 312 can extend around a circumference of the cap body 210, and the circumferential wall 312 can partially enclose the cavity 310. A cavity opening 313 to the cavity 310 can be defined at the first body end 212, and a cavity gasket 314 can extend around the cavity opening 313. The cavity gasket 314 can be configured to seal with the cap cover 280 (shown in FIG. 2) to enclose the cavity 310.

As previously discussed, the antenna covers 318a,b can circumferentially overlap portions of the circumferential wall 312. In the present aspect, the portions can be scalloped portions defined by external scallops 316a,b, respectively. The external scallops 316a,b can extend axially inward into the outer wall surface 290 of the circumferential wall 312 relative to the cap axis 201, shown extending out of the page. As shown, the antenna covers 318a,b can fit within the external scallops 316a,b, respectively.

The nozzle cap 150 can further comprise a pair of antenna printed circuit boards (“PCBs”) 320a,b which can be respectively enclosed within each of the external scallops 316a,b between the respective antenna cover 318a,b and the circumferential wall 312. Each antenna cover 318a,b can define an inner cover surface 322a,b, respectively, which can face the circumferential wall 312. An antenna cavity 324a,b can respectively be defined between each of the inner cover surfaces 322a,b and the scalloped portions of the circumferential wall 312 defined by the external scallops 316a,b. The antenna covers 318a,b can each partially enclose the respective antenna cavity 324a,b. In the present aspect, the antenna PCB strips 320a,b can be secured in facing engagement with the inner cover surface 322a,b.

The nozzle cap 150 can further comprise a pair of spacer strips 326a,b (shown in FIG. 4) disposed within the respective antenna cavity 324a,b. The spacer strips 326a,b can be positioned between the respective antenna cover 318a,b and the circumferential wall 312, and the spacer strips 326a,b can be in facing engagement with the adjacent antenna cover 318a,b and the circumferential wall 312. In the present aspect, the spacer strips 326a,b can comprise an adhesive which can be bonded to either or both of the respective antenna cover 318a,b and the circumferential wall 312. In the present aspect, the spacer strips 326a,b can comprise a compressible material, such as foam, rubber, an elastomer, or any other suitable material. The spacer strips 326a,b can be compressed by the respective antenna covers 318a,b, thereby forming a seal between the antenna covers 318a,b and the circumferential wall 312.

The antenna PCB strips 320a,b can be attached to the inner cover surface 322a,b of the respective antenna cover 318a,b, such as with an adhesive, a tape, or a mechanical fastener, such as hook-and-loop strips, a screw, a bolt, a snap, or any other suitable attachment mechanism. In some aspects, the antenna PCB strips 320a,b can be positioned atop a bottom cover surface 333a,b of the respective antenna covers 318a,b. The bottom cover surfaces 333a,b can be defined within the respective antenna cavities 324a,b.

The spacer strips 326a,b can primarily act as a temporary sealing mechanism for filling the antenna cavities 324a,b with a potting material. With any gaps between the antenna covers 318a,b and the circumferential wall 312 sealed by the spacer strips 326a,b, potting can be poured into each antenna cavity 324a,b in a liquid or amorphous form, and the potting can be allowed to cure. The potting can permanently seal the respective antenna cavity 324a,b, and the potting can permanently secure each antenna PCB strip 320a,b in facing engagement with the inner cover surface 322a,b. The potting can secure the antenna PCB strips 320a,b permanently in position in a manner which resists vibration and impact.

The potting can at least partially be positioned between the antenna PCB strips 320a,b and the circumferential wall 312. In some aspects, the circumferential wall 312 can interfere with transmissions from the antenna PCB strips 320a,b. The potting can maintain a constant gap between the circumferential wall 312 and the respective antenna PCB strips 320a,b, therefore providing consistent transmission tuning of the antenna PCB strip 320a,b. The potting can also seal out moisture, debris, and other foreign matter which could enter the antenna cavities 324a,b and interfere with the operation of the antenna PCB strips 320a,b. By attaching the antenna PCB strips 320a,b to the respective inner cover surfaces 322a,b, the gap between the circumferential wall 312 and the antenna PCB strips 320a,b can be maximized to reduce potential interference.

The nozzle cap 150 can comprise a battery pack 360, a processing printed circuit board ("PCB") 362, and a vibration sensor 380 disposed within the cavity 310. The processing PCB 362 can be attached to a mounting bracket 364 which can be secured within the cavity 310 by a pair of fasteners 366. The vibration sensor 380 can be attached to the circumferential wall 312 within the cavity 310, and the vibration sensor 380 can extend radially inward towards the cap axis 201 (shown extending out of the page).

The battery pack 360, the processing PCB 362, the vibration sensor 380, and the antenna PCB strips 320a,b can all be connected in electrical communication. The vibration sensor 380 can be configured to detect leaks within the fluid system (not shown) by monitoring vibrations travelling up the stand pipe 198 (shown in FIG. 1) and through the fire hydrant 110 (shown in FIG. 1) when the nozzle cap 150 is mounted on the nozzle 140a (shown in FIG. 1). Vibration patterns within the fluid system can indicate the presence of leaks within the fluid system. The vibration sensor 380 can produce voltage readings when the vibration sensor 380 experiences vibrations. These voltage readings can be processed by the processing PCB 362 to determine whether leaks are present, and a signal can be transmitted outwards from the nozzle cap 150 with the antenna PCB strips 320a,b to convey whether leaks have been identified within the fluid system.

FIG. 4 is a front perspective view of the nozzle cap 150 of FIG. 1 with the cap cover 280 (shown in FIG. 2), and the cavity gasket 314 (shown in FIG. 3) removed. As shown, each of the antenna covers 318a,b can comprise an inner layer 422a,b, respectively, and an outer layer 424a,b, respectively. The inner layers 422a,b can define a wide U-shape which can be shaped complimentary to the spacer strips 326a,b as illustrated in FIG. 5. The outer layers 424a,b can respectively define the inner cover surfaces 322a,b (as shown below in FIG. 8), and the outer layers 424a,b can define the outer cover surfaces 218a,b, respectively. The inner cover surfaces 322a,b can be defined opposite from the outer cover surfaces 218a,b. Each antenna cover 318a,b can comprise a pair of pin guides 426a—d, and the pin guides 426a—d can be positioned between the adjacent inner layers 422a,b and outer layers 424a,b, respectively. The antenna PCB strips 320a,b can extend between the respective pin guides 426a—d and outer layers 424a,b.

A pin 428a—d can extend through each of the pin guides 426a—d, and the pins 428a—d can be attached to the respective bottom shelves 240a,b. The antenna covers 318a,b can slide axially with respect to the cap axis 201 along the pins 428a—d to install or remove the antenna covers 318a,b from the cap body 210. When the cap cover 280 (shown in FIG. 2) is attached to the first body end 212, the antenna covers 318a,b can be axially secured between the cap cover 280 and the bottom shelves 240a,b, thereby preventing removal of the antenna covers 318a,b from the cap body 210. Additionally, the cap cover 280 can fully enclose the antenna cavities 324a,b proximate to the first body end 212.

The antenna PCB strips 320a,b can be connected to the processing PCB 362 by wires passing through wire ports 450a—c (wire port 450c shown in FIG. 8) can be exposed. In the present aspect, the wires can be coaxial cable feedlines. The wire ports 450a—c can extend through the circumferential wall 312 from the respective antenna cavity 324a,b to the cavity 310. Each of the wire ports 450a—c can be sealed with a plug 452a—c (plug 452c shown in FIG. 8), respectively. The plugs 452a—c can be split plugs configured to accommodate a wire (not shown) of the respective

antenna PCB strip 320a,b. The wires of the antenna PCB strips 320a,b can extend through the plugs 452a—c and through the wire ports 450a—c into the cavity 310 to connect the antenna PCB strips 320a,b to the processing PCB 362. The plugs 452a—c can seal the wire ports 450a—c around the wires. In the present aspect, the plugs 452a—c can primarily serve as a temporary sealing mechanism for when the potting is poured into the antenna cavities 324a,b, respectively. Once the potting has cured within the antenna cavities 324a,b, each antenna cavity 324a,b can be fully sealed against the elements, dirt, water, or any other foreign matter.

FIG. 5 is a front perspective view of the nozzle cap 150 with the cap cover 280 (shown in FIG. 2), the cavity gasket 314 (shown in FIG. 3), the antenna PCB strips 320a,b (shown in FIG. 3), the coaxial cable feedlines, and the antenna covers 318a,b (shown in FIG. 3) removed. With the antenna PCB strips 320a,b and the antenna covers 318a,b removed, the wire ports 450a,b and plugs 452a,b can be exposed. As shown, each of the bottom shelves 240a,b can each respectively define a lower shelf surface 540a,b and an upper shelf surface 542a,b positioned above the lower shelf surface 540a,b. In the present aspect, each spacer strip 326a,b can rest upon the respective upper shelf surface 542a,b. As described above, the spacer strips 326a,b can define a wide U-shape wherein opposing ends 526a—d of each respective spacer strip 326a,b extend upwards towards the first body end 212.

The cap body 210 can define pin holes 528b—d corresponding to pins 428b—d. A pin hole corresponding to pin 428a can also be defined but is not shown in the present view; however, pin holes 528b—d can be representative of the pin hole of pin 528a. The pin holes 528b—d can extend axially downward into the upper shelf surface 542a,b and towards the second body end 214 relative to the cap axis 201, as shown in FIGS. 5 and 6. The pins 428b—d can be received within the pin holes 528b—d, and the pins 428b—d can be aligned substantially parallel to the cap axis 201.

The cap body 210 can also define a threaded bore 580 which can extend through the circumferential wall 312 substantially perpendicular to the cap axis 201. A threaded end 780 (shown in FIG. 7) of the vibration sensor 380 can threaded engage the threaded bore 580 to attach the vibration sensor 380 to the circumferential wall 312 within the cavity 310.

FIG. 6 is a front perspective view of the nozzle cap 150 of FIG. 1, and FIG. 7 is a side view of the nozzle cap 150 of FIG. 1, each shown with the cap cover 280 (shown in FIG. 2), the cavity gasket 314 (shown in FIG. 3), the antenna PCB strips 320a,b (shown in FIG. 3), the spacer strips 326a,b (shown in FIG. 3), the plugs 452a—c (plugs 452a,b shown in FIG. 4, plug 452c shown in FIG. 8), the pins 428a—d, and the antenna covers 318a,b (shown in FIG. 3) removed. With the pins 428a—d removed, the pin holes 528b—d are shown exposed in FIG. 6. As previously described, the pin holes 528b—d can extend axially downwards, relative to the cap axis 201, into the respective bottom shelves 240a,b of the cap body 210 from the upper shelf surfaces 542a,b towards the second body end 214. In other aspects, the pin holes 528b—d can extend axially downwards into the respective bottom shelves 240a,b of the cap body 210 from the lower shelf surfaces 540a,b towards the second body end 214. In other aspects, the pin holes 528b—d can be threaded, and the pins 428a—d can be replaced by fasteners, such as screws or bolts, which can secure the antenna covers 318a,b to the cap body 210. With the plugs 452a—c removed, the wire ports 450a—c (wire port 450c and plug 452c shown in FIG.

8) can be open and unobstructed. As demonstrated by wire port **450a** in FIG. 7, each of the wire ports **450a**—**c** can extend through the circumferential wall **312** to the cavity **310**. As further shown in FIG. 7, the threaded bore **580** can extend through the circumferential wall **312**, and the threaded bore **580** can receive the threaded end **780** of the vibration sensor **380** to secure the vibration sensor **380** to the circumferential wall **312**.

FIG. 8 is a front exploded view of the cap body **210**, the plugs **452a**—**c**, the pins **428a**—**d**, the spacer strips **326a,b**, the antenna PCB strips **320a,b**, and the antenna covers **318a,b** of the aspect of FIG. 2. The cap body **210**, the pins **428a**—**d**, the spacer strips **326a,b**, and the antenna PCB strips **320a,b** can be translated along the cap axis **201**. The plugs **452a**—**c** can be translated radially outward from their respective wire ports **450a**—**c** relative to the cap axis **201**. The coaxial cable feedlines for the antenna PCB strips **320a,b** are not shown.

As previously described and demonstrated by the inner layer **422a** of the antenna cover **318a**, the inner layers **422a,b** can be shaped complimentarily to the respective spacer strips **326a,b**. Additionally, circumferential lengths of the antenna covers **318a,b**, spacer strips **326a,b**, and antenna PCB strips **320a,b** can correspond to the circumferential length of the respective external scallop **316a,b**. In the present aspects, the external scallop **316a**, the antenna cover **318a**, the antenna PCB strip **320a**, and the spacer strip **326a** can each define a longer circumferential length than the respective external scallop **316b**, the antenna cover **318b**, the antenna PCB strip **320b**, and the spacer strip **326b**. In other aspects, the external scallops **316a,b**, the antenna covers **318a,b**, the antenna PCB strips **320a,b**, and the spacer strip **326a,b** can be equal in circumferential length.

As previously described, the antenna PCB strips **320a,b** can be configured to attach to the inner cover surfaces **322a,b** within the respective covers **318a,b** and between the respective inner layers **422a,b** and outer layers **424a,b**. The antenna PCB strips **320a,b** can be flexible PCBs, and when the antenna PCB strips **320a,b** are attached to the inner cover surfaces **322a,b**, each antenna PCB strip **320a,b** can be shaped as a frustum section. In other aspects, the antenna PCB strips **320a,b** can be shaped as cylindrical sections when attached to the inner cover surfaces **322a,b**.

The antenna PCB strips **320a,b** can each comprise one or more antennas, as shown and further discussed below with respect to FIGS. 9–12. For example and without limitation, antenna PCB strip **320a** can comprise two separate antennas, and a wire (shown in FIG. 4) attached to the first antenna can extend through the wire port **450a** while a wire (shown in FIG. 4) attached to the second antenna can extend through the wire port **450c** to attach the antenna PCB strip in electrical communication with the processing PCB **362** (shown in FIG. 3). Antenna PCB strip **320b** can comprise a third antenna with a wire (shown in FIG. 4) extending through the wire port **450b** to attach the antenna PCB strip in electrical communication with the processing PCB **362**. In the present aspect, the antennas can be different types of antennas configured to wirelessly transmit over different frequency ranges. By separating the antenna PCB strips **320a,b** into the separate external scallops **316a,b**, interference between the antennas of the antenna PCB strips **320a,b** can be reduced. By reducing interference, the separate antenna PCB strips **320a,b** can offer improved performance in range and signal clarity. In other aspects, the nozzle cap **150** can comprise more than two antenna PCB strips **320a,b**, and the cap body **210** can define more than two external scallops **316a,b**.

FIGS. 9–12 show front views of variations of an antenna PCB strip **920** which can be representative of either or both of the antenna PCB strips **320a,b**. In the aspects shown, the antenna PCB strips **920** can each comprise one antenna **910,1010,1110,1210** which can be printed on the antenna PCB strip **920**. In the present aspect, the antenna PCB strips **920** can be flexible PCBs. In the aspect shown in FIG. 9, the antenna **910** can be a Global System for Mobile communication (“GSM”) antenna configured to wirelessly transmit a signal over GSM frequency bands. In the aspect shown in FIG. 10, the antenna **1010** can be an Advanced Metering Infrastructure (“AMI”) antenna configured to wirelessly transmit a signal over AMI frequency bands. In the aspect shown in FIG. 11, the antenna **1110** can be a Global Positioning System (“GPS”) antenna configured to wirelessly transmit a signal over GPS frequency bands. In the aspect shown in FIG. 12, the antenna **1210** can be a Near Field Communication (“NFC”) antenna configured to wirelessly transmit a signal over NFC frequency bands. In other aspects, the antenna PCB strip **920** can comprise one or more antennas configured to wirelessly transmit over any frequency band or range.

The antenna PCB strips **920** can define an arched shape in the present aspect; and the antenna PCB strips **920** can be curved to conform to a curvature of the inner cover surfaces **322a,b** (shown in FIG. 8). Once secured to the inner cover surfaces **322a,b**, the antenna PCB strips **920** can take the shape of a frustum section wherein the bottom edge and the top edge can lie in substantially parallel planes. When installed, the bottom edge can lie flat against the respective bottom cover surfaces **333a,b** (shown in FIG. 3) in the present aspect.

One should note that conditional language, such as, among others, “can,” “could,” “might,” or “may,” unless specifically stated otherwise, or otherwise understood within the context as used, is generally intended to convey that certain embodiments include, while other embodiments do not include, certain features, elements and/or steps. Thus, such conditional language is not generally intended to imply that features, elements and/or steps are in any way required for one or more particular embodiments or that one or more particular embodiments necessarily include logic for deciding, with or without user input or prompting, whether these features, elements and/or steps are included or are to be performed in any particular embodiment.

It should be emphasized that the above-described embodiments are merely possible examples of implementations, merely set forth for a clear understanding of the principles of the present disclosure. Any process descriptions or blocks 50 in flow diagrams should be understood as representing modules, segments, or portions of code which include one or more executable instructions for implementing specific logical functions or steps in the process, and alternate implementations are included in which functions may not be included or executed at all, may be executed out of order from that shown or discussed, including substantially concurrently or in reverse order, depending on the functionality involved, as would be understood by those reasonably skilled in the art of the present disclosure. Many variations 55 and modifications may be made to the above-described embodiment(s) without departing substantially from the spirit and principles of the present disclosure. Further, the scope of the present disclosure is intended to cover any and all combinations and sub-combinations of all elements, 60 features, and aspects discussed above. All such modifications and variations are intended to be included herein within the scope of the present disclosure, and all possible 65

11

claims to individual aspects or combinations of elements or steps are intended to be supported by the present disclosure.

That which is claimed is:

1. A method for manufacturing a nozzle cap, the method comprising:

obtaining a cap body configured to seal a nozzle;
attaching an antenna printed circuit board ("PCB") strip to an inner cover surface of an antenna cover;

inserting the antenna cover into a scallop defined by an outer wall surface of a circumferential wall extending about a circumference of a cap body to position the antenna PCB strip between the antenna cover and the circumferential wall, the circumferential wall defining the outer wall surface, the antenna cover covering the scallop, the scallop extending radially inward into the outer wall surface of the circumferential wall relative to a first portion and a second portion of the outer wall surface, the scallop circumferentially positioned between the first portion and the second portion of the outer wall surface; and

fastening the antenna cover to the cap body.

2. The method of claim 1, further comprising contacting the inner cover surface with a spacer strip positioned within the scallop.

3. The method of claim 1, wherein inserting the antenna cover into the scallop comprises positioning an outer cover surface of the antenna cover flush with the first portion and the second portion of the outer wall surface.

4. The method of claim 1, further comprising pinning the antenna cover to the cap body with at least one pin.

5. The method of claim 1, further comprising mounting a vibration sensor to the cap body.

6. The method of claim 1, further comprising filling an antenna cavity with potting, the antenna cavity defined between the inner cover surface and the circumferential wall, the antenna PCB strip positioned within the antenna cavity.

7. The method of claim 1, further comprising attaching a cap cover to the circumferential wall, the cap cover at least partially enclosing an antenna cavity, the antenna cavity defined between the inner cover surface and the circumferential wall, the antenna PCB strip positioned within the antenna cavity.

8. A nozzle cap comprising:

a cap nut configured to seal the nozzle cap on a nozzle;
a cap body defining a circumferential wall extending about a circumference of the cap body, the circumferential wall defining an outer wall surface, a scallop defined by the outer wall surface and extending into the outer wall surface of the circumferential wall relative to a first portion and a second portion of the outer wall surface, the scallop circumferentially positioned between the first portion and the second portion of the outer wall surface;

an antenna cover positioned within the scallop, the antenna cover secured to the cap body by at least one pin; and

12

an antenna printed circuit board ("PCB") strip positioned within an antenna cavity defined between the antenna cover and the circumferential wall.

9. The nozzle cap of claim 8, wherein the cap body defines at least one pin hole, and wherein the at least one pin hole receives the at least one pin.

10. The nozzle cap of claim 8, further comprising a cap cover coupled to the circumferential wall, the cap cover at least partially enclosing the antenna cavity.

11. The nozzle cap of claim 8, wherein the antenna PCB strip is coupled to an inner cover surface of the antenna cover.

12. The nozzle cap of claim 8, further comprising a spacer strip positioned between the antenna cover and the circumferential wall.

13. The nozzle cap of claim 8, further comprising a second antenna cover and a second antenna PCB strip each positioned within a second scallop defined by the circumferential wall.

14. The nozzle cap of claim 8, further comprising a vibration sensor coupled to the cap body.

15. A method for manufacturing a nozzle cap, the method comprising:

obtaining a cap body configured to seal a nozzle;
positioning a first antenna cover in a first scallop defined by an outer wall surface of a circumferential wall extending about a circumference of the cap body with a first antenna printed circuit board ("PCB") strip positioned between the first antenna cover and the circumferential wall, the circumferential wall defining the outer wall surface, the first scallop extending inwards into the outer wall surface relative to a first portion and a second portion of the outer wall surface, the first scallop circumferentially positioned between the first portion and the second portion of the outer wall surface; and

positioning a second antenna cover in a second scallop of the circumferential wall with a second antenna PCB strip positioned between the second antenna cover and the circumferential wall.

16. The method of claim 15, wherein an outer cover surface of the first antenna cover is positioned flush with the first portion and the second portion of the outer wall surface.

17. The method of claim 15, further comprising attaching a cap cover to the circumferential wall.

18. The method of claim 17, wherein attaching the cap cover to the circumferential wall comprises at least partially enclosing a first antenna cavity and a second antenna cavity, the first antenna cavity defined between the first antenna cover and the circumferential wall, the second antenna cavity defined between the second antenna cover and the circumferential wall.

19. The method of claim 15, further comprising attaching a vibration sensor to the cap body.

20. The method of claim 15, further comprising positioning a potting material between the first antenna cover and the circumferential wall.
